UNITED STATES PATENT OFFICE.

HARRISON L. STALEY, OF MARTINSVILLE, INDIANA.

GEARING FOR WASHING-MACHINES.

SPECIFICATION forming part of Letters Patent No. 695,244, dated March 11, 1902.

Application filed May 20, 1901. Serial No. 61,026. (No model.)

To all whom it may concern:

Be it known that I, HARRISON L. STALEY, a citizen of the United States, residing at Martinsville, in the county of Morgan and State 5 of Indiana, have invented certain new and useful Improvements in Gearing for Washing-Machines; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 My invention relates to the means for operating washing-machines in which there are parts partaking of rotative motions and also vertically reciprocatory motions, the objects of the invention being to provide simple and 20 compact gearing for washing-machines which may be cheaply constructed and be durable and economical in use.

The invention consists in the novel parts and in the combination and arrangement of 25 parts, as hereinafter particularly described, and pointed out in the claims.

Referring to the drawings, Figure 1 represents a central vertical sectional view of a washing-machine and a side elevation of the 30 operating mechanism constructed substantially in accord with my invention; Fig. 2, a transverse sectional view of the inner and outer vertical gearing-spindles; Fig. 3, a fragmentary view in elevation, showing the front 35 part of the dual-reciprocating-motion gear; Fig. 4, a fragmentary elevation view of a portion of the gear-frame; Fig. 5, a top plan view of the complete gear upon a machine; Fig. 6, a bottom plan view, on a reduced scale, of 40 the rubber and pounder combined to which my gearing is applied and also illustrating substantially a top plan of the bottom of the tub; Fig. 7, a perspective view of the rotator for moving the articles that may be acted 45 upon in the tub, and Fig. 8 a fragmentary top plan view of the combined rubber and pounder.

Similar reference characters in the several figures of the drawings refer to like parts. 50 In explanation of the operative functions of my invention I show a suitable tub A, having a tight bottom A', preferably provided

with radial ribs *a* or with a cover of corrugated metal. The tub has a lid B extending nearly over the whole top of the tub, the remaining portion being covered by a smaller like part B', which is attached to the tub, hinges *d* connecting the parts B and B', so that the lid part may be raised at will, and this preferably has a latch *b* of suitable form. 55 60

A frame-base C is secured to the top of the lid B, and it has erected thereon a suitable frame D, having an overhanging head E. On the base C is also a shaft-support *e* of suitable form. In the frame D is a journal-bearing *f*, in which is mounted a rotative shaft F, the latter being also journaled on and partially supported by the support *e*. A balance-wheel *h*, (or a crank-arm,) having a handle *i*, is secured to the outer overhanging 70 end of the shaft F, whereby to operate the gearing. At the inner end of the shaft F a bevel-gear or toothed wheel G is secured thereto, the shaft having a guide-pin *j* attached thereto projecting beyond the gear-wheel centrally with the center of the shaft, of which the pin is preferably a part reduced 75 in diameter.

The base C comprises also a journal-bearing C', having a suitable aperture to receive 80 a vertical rotative shaft, and the head E is likewise designed for a companion journal-bearing for such shaft, and the frame as a whole comprising the parts C C' D E *e* may be made in any suitable number of separate 85 sections for convenience in assembling the mechanism, as will be obvious. In the lid B is a suitable aperture corresponding to the aperture in the bearing C'.

In the frame-bearings is a vertical spindle 90 or shaft H, having a circular exterior and smooth, so that it may move longitudinally as well as rotate in the bearings. In the upper end of the shaft are suitable screw-threads into which is fitted a screw-threaded rod K, 95 having a detachable lever-handle *u*. The shaft H is hollow throughout, the portion below the screw-threads being square or rectangular in cross-section, and in this part is slid- 100 ingly fitted an inner shaft J, having a cross-sectional area corresponding to the interior of the spindle H, so that when the latter rotates it will rotate the shaft J. Obviously this is illustrative rather than arbitrary, as a

spline may be employed in lieu of the rectangular forms for the purpose. The shaft J is connected at its upper end to the screw-rod K by means of a T-head t, attached to the end 5 of the rod and inserted into a suitable slot in the shaft J. The lower end of the shaft J has a foot w, to which is secured a suitable combined rubber and pounder L, having radial ribs v at the under side thereof or a layer 10 of corrugated metal and having also a number of apertures y.

A rotator M, comprising a plate having projecting pins N, is mounted upon the rubber L, the pins inserted in the apertures y 15 and projecting therethrough. The plate has a central aperture p, through which the shaft J extends, this shaft having a stop-pin q or a suitable shoulder to prevent the rotator L from rising above a prearranged distance 20 above the pounder L.

Having illustrated and explained such elements as my invention is designed to operate with and also minor parts included in my invention, I will now describe the principal 25 element in my improved gearing, as follows: Attached to the spindle H intermediately of its ends or forming an integral part of the shaft is a dual-reciprocating-motion gear engaged by and operated by the toothed wheel 30 G. This dual-motion gear is employed for imparting from the rotative motion of the shaft F to the spindle H intermittent oscillatory and reciprocatory motions, which are thereby transmitted to the rubber and 35 pounder and to the rotator above described or to other suitable devices that may be employed in churning and ice-cream freezers and the like. The dual-motion gear comprises a body portion having at the upper part thereof 40 a segment I' of a bevel-gear or toothed wheel and having at the lower part thereof a segment I² of a bevel-gear or toothed wheel, each having teeth k facing the teeth of the opposite segment and meshing with the teeth of 45 the wheel G. At one side of the body are two reversed segments of bevel-gear or toothed wheels I and I³, respectively, having also teeth k arranged so that these are segments of internal gear-wheels and forming continuations of the segments I' and I², connecting one 50 with the other at two parts of each, so that a toothed wheel meshing therewith may travel continuously in contact with the several segments, rolling about the axis of the shaft H 55 in one direction, then longitudinally of the shaft, then about it in the opposite direction, and then again longitudinally thereof; but in practice in the present case the axis of the wheel G is stationary, while the segmentary 60 gears partake of the reciprocatory oscillating motions. In the body of said segmentary gear is a continuous guide-channel l, corresponding in direction to the contour of the pitch-line of the segmentary gear-teeth, the 65 channel extending about the axis of the shaft H as two parallel branches with a rib m between them and connected at their ends by

semicircular branches about the ends of the rib, and in this channel operates the guide-pin j to maintain contact of the gear-teeth. 70 Projecting from one side of the segment I² is a guide-pin r and from the opposite side a like pin r'; but these pins may be attached either to the segment I' or to the spindle H, and they are designed to form contact with a 75 vertically-disposed guide-bar n, attached to the gear-frame D, although in some cases these pins and the guide-bar may be dispensed with.

In practical use let it be supposed that the 80 articles to be washed are placed in the tub with the washing liquid and the relative position of the spindle H is at its lower limit of travel, as indicated in Fig. 1, the rubber L having been depressed upon the articles with 85 a suitably light degree of pressure by means of the screw-rod K, the rotator M being by this action pushed up to the position shown. Now if the wheel or crank-arm h be put in motion in the direction of the arrow the parts 90 J, H, K, L, and M will be moved rotatively, the part L performing the rubbing operation until the wheel G has traversed the segment I' and come in contact with the segment I, when the parts J K L will by said contact be 95 elevated, while the pins N drop through their apertures as the part L rises and engage the clothes or articles in the tub. Immediately before these parts and the segment I rises by the action of the wheel G the pin r will have 100 passed under the bar n, so that as all the parts rise the pin may engage the opposite side of the bar and prevent disengagement of the gear-teeth. When the parts described have risen until the wheel G comes in contact with the segment I², a reversed rotary motion will begin and the pin R will have reached the top of the bar n and pass over it on the return motion, and in this reverse movement the pins N will rotate the clothes 105 against the rubbers or ribs a. When the wheel G shall have traversed the segment I², it will come in contact with the segment I³, the pin r' passing above the bar n and then down the side thereof seen in the view in Fig. 1 as 110 the segment I³ is forced downward, together with the parts H J K L, until the segment I² comes into action, when the several positions of the parts as shown in Fig. 1 will have been again reached. In its downward movement 115 the part L acts as a pounder and also as a piston to such extent as to force the washing liquid through the articles in the tub, and likewise the liquid will be sucked upwardly through the articles by the part L when it 120 rises. It will thus be seen that the part L operates alternately in rotative and reciprocating vertical movements.

Having thus described my invention, what I claim, and desire to secure by Letters Patent, is—

1. A mechanical movement mechanism including a rotative driving-shaft, a toothed driving-wheel secured to the rotative shaft, a

driven shaft, and a dual-reciprocating-motion gear comprising two segments of toothed wheels facing each other and two other connecting-segments of toothed wheels practically facing each other and all connecting alternately with the driving-wheel, whereby the rotative driving-shaft may impart to the driven shaft alternating oscillatory and reciprocating motions.

10 2. In gearing for washing-machines, a driven spindle or shaft adapted to be attached to the rubber and pounder, a dual-reciprocating-motion gear secured to the driven spindle and comprising two segments of external 15 toothed wheels having an identical axis and two connecting-segments of internal toothed wheels having an identical constructive axis at right angles to the axis of the first-described segments, and a toothed driving-wheel 20 engaging alternately the said segments.

3. In gearing for washing-machines, a vertically-movable rotative shaft, a longitudinally-adjustable shaft supported within said rotative shaft, means for binding said longitudinally-adjustable shaft in said rotative shaft, a toothed driving-wheel, and a dual-reciprocating-motion gear comprising segments of toothed wheels of which two segments are of external wheels and two segments are of 30 internal wheels in different planes connected together and secured to said rotative shaft and engaged by said toothed driving-wheel.

4. In gearing for washing-machines, a gearing-frame, a vertically-movable rotative shaft 35 mounted in the frame, a dual-reciprocating-motion gear comprising a body portion having two parallel channels connected at their ends by curved channels forming an endless channel provided with gear-teeth extending 40 along the course of said channel at the outside thereof, a driving-shaft, a driving toothed wheel secured to the driving-shaft and engaging said gear-teeth, a guide-pin extending into said channel, a guide-bar secured to said 45 gearing-frame, and guide-pins projecting from said dual gear so as to alternately engage opposite sides of said guide-bar.

5. In gearing for washing-machines, a gear-frame, a hollow driven spindle mounted in 50 the frame and movable vertically, a dual-reciprocating-motion gear secured to the driven spindle, a driving-wheel engaging said gear, a longitudinally-adjustable shaft in the said hollow spindle, means whereby to bind said 55 shaft in adjusted positions to said hollow spindle, a guide-bar attached to the gear-frame, guide-pins projecting from said gear so as to engage said bar when said gear trav-

erses in vertical directions, a guide-channel in said gear, and a guide-pin projecting into 60 said channel.

6. In gearing for washing-machines, a vertical hollow spindle movable longitudinally and also rotatively and having the screw-thread in the upper end thereof, a vertical 65 shaft carried in said hollow spindle and movable longitudinally therein and having the slot near the upper end thereof, a screw-rod engaging said screw-thread and having a head in said slot, a dual-reciprocating-motion 70 gear secured to said vertical spindle, a horizontal rotative shaft, a driving-wheel secured to the horizontal shaft and engaging the dual gear, whereby when the driving-wheel is rotated the said vertical shaft is caused to alternately move longitudinally and also move 75 rotatively partially about its axis, and whereby also said vertical shaft may be adjusted in its vertical travel.

7. In gearing for washing-machines, a dual- 80 reciprocating-motion gear comprising a body portion having two parallel channels connected at their ends by curved channels forming an endless channel, and segments of toothed bevel gear-wheels connected together 85 in different planes so as to form an endless curved gear-rack extending partially about the ends and along two sides of the body portion, substantially as shown, in combination with the rotative shaft having the guide-pin 90 operating in said endless channel, and the bevel-toothed wheel engaging said endless rack.

8. In a gearing for washing-machines, the combination of the gearing-frame, the dual- 95 reciprocating-motion gear comprising the four connected segments of toothed wheels and having the endless guide-channel in the body thereof within the contour lines of said segments, the horizontal driving-shaft 100 mounted in said frame and having the guide-pin projecting into said channel, the toothed driving-wheel secured to said driving-shaft and engaging said dual gear, the guide-bar attached to said frame, the guide-pins projecting from said dual gear to engage said 105 guide-bar, the vertical hollow spindle secured to said dual gear, the vertical shaft in said hollow spindle, and a binder for said vertical shaft, substantially as set forth.

In testimony whereof I affix my signature in presence of two witnesses.

HARRISON L. STALEY.
